(57) **CLAIM**

The ornamental design for a smartphone camera mount, as shown and described.

DESCRIPTION

FIG. 1 Provides a rear perspective view of a smartphone camera mount.

FIG. 2 Provides a left side perspective view of a smartphone camera mount.

FIG. 3 Provides a rear planar view of a smartphone camera mount.

FIG. 4 Provides a front planar view of a smartphone camera mount.

FIG. 5 Provides a left side elevation view of a smartphone camera mount; and,

FIG. 6 Provides a right side elevation view of a smartphone camera mount.

The broken lines showing a camera, a monocular and tripod, and various screw components depict environmental subject matter and form no part of the claimed design.
